CLAIM

The ornamental design for an inserter, as shown and described.

DESCRIPTION

FIG. 1 is a perspective view of an inserter.

FIG. 2 is a front view of the inserter, the back view being the same as the front view.

FIG. 3 is a left side view of the inserter, the right side view being the same as the left side view.

FIG. 4 is a top view of the inserter; and,

FIG. 5 is a bottom view of the inserter.

The broken lines shown in the figures are included for the purpose of illustrating portions of the inserter and form no part of the claimed design.
